CHECK STRAP

This invention relates to check straps, and more particularly to a unitary check strap of the type having a guide rod carrying a loop of elongated flat strap material where a second elongated flat strap portion is carried integrally with one end of a first flat strap portion for joining the ends of the loops so that the use of special fasteners may be avoided.

The check strap assembly illustrated herein is an improvement upon check straps of the type in U.S. Pat. No. 3,228,429 issued on Jan. 11, 1966, to Chester R. Messer. In check straps of this type a tie strap must be used to connect the free ends of the loop which are mounted upon the guide rod. It is necessary that the tie strap extend in a flat position directly between the ends, otherwise, it will engage loom parts, such as the motor housing, resulting in damage to both parts during weaving. It is also important that the loops of such check strap assemblies be replaceable without the necessity for temporarily removing the picker stick. This is accomplished in the above patent through the use of J-hooks at both ends of the loops for mounting the tie strap thereon. It has been necessary that two J-hooks be carried at each of the free ends of the loop. Special fasteners of the variety illustrated in the above patent include the hook and shank portions which carry collars and set-screws.

The present invention contemplates the provision of a loop portion for the check strap assembly possessing the advantages enumerated in connection with the check strap assembly of the above patent, while avoiding the use of special fasteners which have been found to be inordinately expensive and troublesome. The invention contemplates doing this through the provision of a unitary loop structure which is replaceable without removal of the picker stick upon the guide bar, and which avoids damage to associated loom parts.

Accordingly, an important object of this invention is the provision of a check strap of the type employing a guide rod wherein the loop may be installed without removing the picker stick and the means for connecting the ends joined to the ends without the use of special fasteners.

Another important object of the invention is the provision of a loop for a check strap assembly of the type described possessing improved wear characteristics, and which avoids damage to adjacent loom parts.

The construction designed to carry out the invention will be hereinafter described, together with other features thereof.

The invention will be more readily understood from a reading of the following specification and by reference to the accompanying drawing forming a part thereof, wherein an example of the invention is shown and wherein:

FIG. 1 is a top plan view, with parts in section, illustrating a check strap assembly constructed in accordance with the present invention positioned upon a loom;

FIG. 2 is a perspective view further illustrating the loop of the check strap assembly illustrated in FIG. 1; and

FIG. 3 is a longitudinal sectional elevation taken on the line 3-3 in FIG. 2.

Referring more particularly to the drawing, a check strap assembly of the type having a guide rod carrying a loop of elongated flat strap material is illustrated. The loop encompasses a loom picker stick, and is positioned for sliding movement adjacent each end thereof on the guide rod. Means for connecting the ends of the loop include, a first elongated flat strap portion A extending between the ends maintaining constant spacing therebetween during weaving against the action of the picker stick tending to separate the ends. A second elongated flat strap portion B, integral with one end of the first elongated flat strap portion, extends laterally therefrom substantially at a right angle thereto for reception upon the guide rod joining the ends of the loops. Thus, the check strap may be installed on the loom without removing the picker stick and the means for connecting said ends joined to said ends without the use of special fasteners. The first elongated flat strap portion A is an integral extension of a portion C of the loop. The loop has a plurality of plies, an outer ply being of leather. The

first elongated flat strap portion A is an integral extension of the outer ply at substantially a right angle thereto, and the second elongated flat strap portion B is integral with the free end of the first elongated flat strap portion. The angles are formed in said outer ply by the application of heat and pressure to an impregnated leather strap.

The loop of the check strap assembly illustrated is broadly designated at 10, and includes an outer ply 11 and an inner ply 12. The end portion includes outer inserts or clamping members 13, and inner inserts or clamping members 14. These inserts build up the end portions and fortify and reinforce them for sliding movement upon the guide rod 15. The guide rod 15 is positioned as by a lug 16 in a horizontal position between a bracket which is not shown, but which is attached to a part of the loom lay frame. The loop is engaged by the usual friction fingers 17, 18 and 19 which retard the movement of the picker stick 20 on a checking stroke. The loop is retained upon the guide rod as by washer portions 21 which are positioned by collars 22 which, in turn, are fixed to the guide rod 15 as by setscrews 23.

As is best seen in FIG. 3, the built-up end portions of the loop 10 include a short reinforcing member 24 and is secured by rivets 25, which include washers 25a on their inner ends. The first elongated flat strap portion A has a second elongated flat strap portion B integral with one end thereof as is best illustrated in FIG. 3. These portions are joined integrally by a 90° bend illustrated at 26. It will be observed that the second flat strap portion B is not otherwise connected to the adjacent portion of the loop, but simply has an opening 27 corresponding with the opening 28, illustrated at the other end of the loop for reception upon the guide rod 15. Preferably, the tie portion or first elongated flat strap portion A is integral with the portion C of the flat strap material forming the outer ply 11. The first elongated flat strap portion A is connected integrally by the 90° bend 29 to the portion C. If the elongated flat strap portions B and C are integrally joined as by the 90° bends 26 and 29, it will be unnecessary to use any special fasteners on either end of the loop.

Preferably, all of the elements which comprise the loop as described above, are made from leather except, of course, for the rivets 25, washers 25a associated therewith, and the portions 24 which may be of suitable plastic.

The leather is preferably treated as described in my copending application entitled loom check strap, Ser. No. 739,059, filed Jun. 21, 1968.

The leather is immersed in a liquid polymeric composition which comprises a resin preferably of the thermosetting variety. The resin is applied to the tanned leather while in a natural or raw state so that the interstices between the leather fibers are sufficiently open to permit substantial penetration of the resin into the leather. Preferably, using the liquid polymeric composition described below, the leather remains immersed for about 45 minutes. While immersion, as described above is preferable, and is carried out preferably to the extent that the resin penetrates uniformly throughout the leather, it may be possible to apply the resin composition by brushing or spraying, or by any other suitable means before or after compression described below so long as substantial impregnation occurs.

The liquid polymeric composition preferably includes a resin and a curing agent therefor so that the resin composition is thermosetting in nature. A polyurethane resin has been found to produce especially desirable results. One such polyurethane composition which has been found acceptable includes a pigmented polyester having a wet weight of 43.42 out of 100 of which .42 is zinc octolite and 8 percent is ethyl acetate. The composition also includes a polyisocyanate 7:56 parts which is 75 percent ethyl acetate. An amine in the form of ethyl diethanolamine in the amount of .24 parts is included. An ester solvent in the form of ethyl acetate is added in an amount of 48.78 parts to make up 100. While a resin of the polyurethane type is thought to be preferable, it may be possible that another type of resin, such as an epoxy resin with curing agent may be used.

Preferably, the loop is totally immersed. The polyester is cured by the polyisocyanate curing agent, preferably by applying heat, and it is preferred that pressure accompanies the application of heat. The heat and pressure acting as described below, form smooth side surfaces on the leather D.

The impregnated leather members are placed upon a flat platen of a press (not shown). Preferably, the press is heated to about 175° F., and a pressure of about 3,500 p.s.i. is applied by the press for about 45 to 90 seconds. The leather is then cut to strips of the desired dimensions. The 90° bends are then formed in the leather while it is still hot or preheated by placing the strap portion associated in the press at about 175° F. for another application of heat and pressure, about 200 p.s.i. for about 2 to 5 seconds.

While a preferred embodiment of the invention has been described using specific terms, such description is for illustrative purposes only, and it to be understood that changes and variations may be made without departing from the spirit or scope of the following claims.

I claim:

1. For use in a check strap assembly of the type having a guide rod carrying a loop of elongated flat strap material, encompassing a loom picker stick, for sliding movement adjacent each end thereof on said guide rod, the improvement

including, means for connecting said ends of said loop comprising, a first elongated flat strap portion extending between said ends maintaining constant spacing therebetween during weaving against the action of the picker stick tending to separate the ends, a second elongated flat strap portion integral with one end of the first elongated flat strap portion and extending laterally therefrom substantially at a right angle thereto for reception upon the guide rod joining said ends of said loops, whereby the check strap assembly may be installed on the loom without removing the picker stick and the means for connecting said ends joined to said ends avoiding the use of special fasteners.

15 2. The structure set forth in claim 1, wherein said first elongated flat strap portion is an integral extension of a portion of said loop at a right angle thereto.

20 3. The structure set forth in claim 1, wherein the loop has a plurality of plies, an outer ply being of leather, said first elongated flat strap portion being an integral extension of said outer ply, and said second elongated flat strap portion being integral with the free end of said first elongated flat strap portion, said angles being formed in said outer ply by the application of heat and pressure to an impregnated leather strap.
